EASY OPEN CONTAINER WITH RECLOSE

Filed Dec. 22, 1961

Fig. 1

Fig. 3

A technical line drawing of a stepped rectangular block. The block is shown in perspective, revealing a central rectangular cavity. The top edge of the block is characterized by a series of vertical, parallel, and slightly inward-curving lines, creating a ribbed or stepped profile. The bottom edge is also stepped, with a wider base and a narrower top. The overall shape is a truncated rectangular prism.

EASY OPEN CONTAINER WITH RECLOSE
Alfred Edward Ballocca, Wheaton, and James Hampton Groves, Barrington, Ill., assignors to American Can Company, New York, N.Y., a corporation of New Jersey

Filed Dec. 22, 1961, Ser. No. 161,535
2 Claims. (Cl. 206—46)

This invention relates to hermetically sealed containers having easy open and reclosure features and to a method for making the same containers. Specifically, it pertains to a container for gas generating products having a closure construction especially adapted to provide hermeticity for the product stored therein but which may be easily opened to provide access to the product and thereafter replaced as a reclosure.

Containers specially constructed for containing gas generating products are well known in the art. They enjoy wide utility for both pressure and vacuum packing a great variety of such products. Generally, these containers are well built with closure and seam constructions admirably suited to withstand the internal pressures generated by the contents and the pressure differential acting on the closure due to the conditions of packing. The numerous types of metal cans for packing roasted ground coffee are typical of these containers. Although these containers possess exceptional preserving and strength characteristics, all have a common disadvantage. That is the fact that a tear strip, either formed integrally, welded or otherwise formed as an intricate part of the end seam structure, is required to open the container. Tear strips do not provide as easy a means for opening a container as desired, since they are troublesome to operate and at times have been known to break or function improperly. Moreover, in those tear strip containers where the end closure doubles as a reclosure, the closure and seam structure is somewhat complex and therefore presents an additional disadvantage of a more costly container.

An important object, therefore, of the present invention is to provide a container for gas generating products which is simple in construction and easy to open.

Another object of this invention is to provide a container for gas generating products which is adapted to be hermetically sealed but which may be easily opened for access to the product and thereafter reclosed.

Another object of this invention is to provide a container for gas generating products to be hermetically sealed with a closure adapted to withstand mild internal gas pressure but which may be easily removed for access to the product and thereafter replaced as a reclosure.

A further object of this invention is to provide a method for making a hermetically sealed container for gas generating products, which is simple in construction and easy to open.

Still another object of this invention is to provide a method for making a container hermetically sealed with a closure which is adapted to withstand mild internal gas pressure but which may be easily removed for access to the product and thereafter replaced as a reclosure.

Numerous other objects and advantages of the invention will be apparent as it is better understood from the following description, which, taken in connection with the accompanying drawings, discloses a preferred embodiment thereof.

2

It has been found that these objects may be accomplished by providing a tubular container body and a skirted closure adapted to sealingly engage an end of the body, placing a skirted membrane of gas impermeable material interiorly of the closure, applying an adhesive to the interior of the membrane skirt, pressing the closure frictionally onto the end of the body so that the membrane conforms to the end of the body and is adhesively sealed over the peripheral wall of the body adjacent the end, and securing the skirted closure to the body with a strip of shear resistant tape wound peripherally about the closure skirt and adjacent body wall.

Referring to the drawings:

FIGURE 1 is a perspective view of a container made in accordance with the invention;

FIG. 2 is an exploded sectional view showing parts of the container of FIG. 1 in an attitude immediately prior to assembly; and

FIG. 3 is a sectional view taken substantially along lines 3—3 of FIG. 1 showing the parts of the container in assembled relation.

As a preferred or exemplary form of the invention, FIG. 1 illustrates a contained 10 having a tubular body 11 and a closure 12 assembled to one end of the body. 25 In accordance with customary practice, the other end of the container is left open and shipped in this form to the packer along with a metal end which is double seamed to the container after the contents have been placed therein. The contents may be any gas generating product 30 requiring a container specifically adapted to maintain effective hermetic protection of the contents and withstand the pressure differential acting on the closure and seam construction as a result of the conditions of packing. For example in the case of a product packed under pressure, the container must be constructed to maintain hermeticity and withstand the internal pressure which tends to build up due to gases generated by the product during storage. Roasted ground coffee is typical of such a product, but it will be understood that the container may 40 be used to package other products as well, whether pressure, vacuum, or atmospherically packed.

FIGURE 2 illustrates the components of container 10 in an attitude preparatory to final assembly. In the form shown, body 11 is rolled at its end into an inwardly projecting open curl 13 defining a rounded lip extending about the entire periphery of the end of the body. Spaced from curl 13 is an outwardly projecting peripheral bead 14 which may be rolled or otherwise formed in the wall of body 11 a predetermined distance from curl 13. Preferably, the outermost wall of bead 14 is flat and presents a smooth flat exterior surface which coincides substantially with the exterior surface of closure 12 when assembled to the container body. However, it will be understood that the end of body 11 may be necked-in to 55 accommodate the closure, in which case the wall of the body below the necked-in portion is of a continuous and uniform diameter. In all other respects, body 11 is similar to any other conventional metal can body.

Closure 12 is in the form of a cup-shaped slip cover 60 having a depending peripheral skirt 15 integral with a generally planar central panel 16. The interior diameter of the skirt is slightly greater than the exterior diameter of body 11 and has an exterior diameter substantially the same as the bead 14 of the body. This ensures that the 65 closure fits snugly over the end of the body with the skirt of the closure forming a more or less flush surface

with the bead 14 or, where the body is necked-in, as hereinbefore mentioned, with the body wall generally. At the juncture of skirt 15 and panel 16 is an annular groove 17 formed to conform substantially to the exterior contour of curl 13. The interior radius of groove 17 5 may be slightly larger than the radius of curl 13 for reasons to be hereinafter explained. An outwardly projecting annular bead 18 may be formed in skirt 15 as a finger grip to facilitate handling the closure, if desired.

A thin membrane or liner 30 is shown inserted within 10 the cup-shaped closure 12. Preferably, the liner is of a gas impermeable material, such as metal foil or plastic. This liner conforms substantially to the interior contour 15 of the closure and includes a skirt portion 31 which terminates just short of the end of skirt 15 of the closure. Liner 30 may be placed within the closure in any desired manner, but it is preferred that it be drawn into the closure at the time the closure itself is being formed. This is considered a simpler operation than forming the liner 20 separately and ensures good conformity to the contour of the closure 12.

An adhesive 32 is applied to the inner surface of the skirt portion 31 of the liner. A variety of hot melt, thermosetting, and thermoplastic adhesives are admirably suited for bonding liner 30 to the end of the container body. Preferably, a curable adhesive, such as a vinyl 25 resin plastisol, is used for this purpose and is applied as a thin film around the interior of the liner skirt. As hereinbefore mentioned the groove 17 in the closure may be formed slightly oversized with respect to curl 13 on the end of the body so that the adhesive has room to spread over a substantial portion of the curl and adjacent body wall to ensure an effective seal.

The assembled closure and liner are then pressed onto 30 the end of the container body, as is illustrated in FIG. 3. Liner 30 is thus tightly pressed against curl 13 and the adjacent wall surface of body 11, with adhesive 32 being 35 spread over a substantial portion of the curl and adjacent wall surface. Where the adhesive 32 is a plastisol as hereinbefore mentioned, curing may be accomplished 40 by heating the plastisol to a temperature of 350° F. for a period of approximately three minutes to firmly seal the liner to the container body. Thus, liner 30 in effect becomes an inner closure or frangible membrane which 45 remains sealed to the container body when closure 12 is removed and is readily rupturable to provide access to the contents of the container.

Closure 12 is secured to body 11 by a band of adhesive 50 tape 33. Preferably this tape is wound completely around the container to overlap a portion of closure skirt 15 and the flat surface of peripheral bead 14 in the body wall. Where the product is gas generating and particularly when pressure packed, the build up of pressure 55 within a container during storage will distend liner 30 and tend to force the closure off. Accordingly, tape 33 and the adhesive thereon must have the characteristics to hold the closure on against the force of this internal gas pressure. For this purpose, the tape itself must have a reasonably high tensile strength, both longitudinally and transversely, to enable it to be readily removed by the consumer without breaking and to withstand blow-off pressure. The adhesive bonding the tape to the container must also have high shear strength to resist blow-off 60 pressure while at the same time possessing low peel strength to enable its easy removal from the container. A variety of hot melt and thermosetting adhesives are admirably suited for this purpose.

As an alternative to adhesive tape 33, wide circumferential bands of shrinkable plastic can be used to seal the closure to the container body. In this case, frictional 70 resistance of the plastic band shrunken tightly about skirt 15 and bead 14 would be in excess of the force tending to lift the closure 12 off the container body. In either case, it will be understood that the tape or band 33 must be of sufficient width and cover enough of the respec-

5 tive surfaces of the closure skirt and body wall to afford the necessary resistance to relative movement of these surfaces. If desired, the tape may be sufficiently wide to extend from below bead 14 in the body wall to above bead 18 in the closure, thereby providing wide locking engagement over a greater surface. As well as effectively sealing the closure to the container, the tape or band provides a continuous surface surrounding the joint between the closure and body, thus giving the end of the container a neat and smooth appearance. It will be readily appreciated that the ease by which tape 33 may be removed by the consumer is far greater than that of metal tear strip containers and that the only tools needed, if any, would be for initiating peeling of the tape and rupturing the liner.

10 When the tape or band 33 is removed by the consumer, the gas pressure inside the container tends to lift closure 12 and thus facilitates its easy removal. As mentioned hereinbefore, membrane 30 remains tightly sealed to the 15 end of the container and is easily ruptured to provide access to the contents. Closure 12 may thereafter be replaced as a reclosure to preserve the freshness of the contents until completely consumed. Thus, there is provided a container construction well suited for hermetically 20 packing gas generating products and which affords easy 25 opening as well as a reclosure feature for preserving the freshness of the contents far beyond the time of initial use.

25 Although the invention has been described in connection for gas generating products, it will be understood that its utility will apply as well to inert products, whether 30 pressure, vacuum or atmospherically packed. In the packing of those products where blow off pressure is not a serious problem, it will be understood that the tape 33 need not be applied necessarily in continuous encircling 35 engagement with the container but may be applied in short spaced strips about the periphery or, if desired, as one or more strips extending over the cover and longitudinally 40 of the container body.

45 It is thought that the invention and many of its attendant advantages will be understood from the foregoing description and it will be apparent that various changes may be made in the form, construction and arrangement of parts and that changes may be made in the steps of the method described and their order of accomplishment without departing from the spirit and scope of the invention or sacrificing all of its material advantages, the form hereinbefore described being merely a preferred embodiment thereof.

We claim:

1. A package comprising:
a tubular container having at one end thereof a substantially straight body wall portion terminating in a curl which circumscribes a container opening; gas-producing contents within said tubular container; a gas-impermeable inner liner adhesively affixed to said container straight body wall portion and curl to hermetically seal said container opening;
2. A closure having a peripheral groove overlying and substantially conforming to said curl and a depressed central panel adapted to depress into said container opening the portion of the inner liner beneath said central panel;
3. Said closure also including a skirt integral with and depending from said peripheral groove in spaced juxtaposition to said straight body wall portion; and an encircling sealing band attached to said container and said closure skirt sealing said closure to said container and positioning said closure with said central panel depressing said inner liner into said container opening;
4. Said sealing band being manually removable whereupon the gas produced by said contents forces said depressed inner liner out of said container opening thus lifting said closure to facilitate easy removal thereof.

2. A package as defined in claim 1 but further characterized by an enlarged container body wall portion adjacent said straight body wall portion and substantially congruent to said closure skirt, said sealing band being attached between said skirt and said enlarged body wall portion.
